JOHN S. O'HARE, OF DENVER, COLORADO, ASSIGNOR OF ONE-HALF TO R. M. AITKEN,
OF DENVER, COLORADO.

SCREED SUPPORT.

Application filed February 10, 1927. Serial No. 167,216.

This invention relates to improvements in means for supporting screeds while constructing concrete floors.

It is now quite common to construct buildings entirely of concrete or in which the floors are also made of concrete. The construction of such buildings requires that a form be first constructed of wood or other suitable material for the support and the reception 10 of the concrete grout. In the construction of concrete floors, a false floor is first laid and properly supported. The tie rods or reinforcing bars are then put into place and supported at a proper height above the top 15 of this floor, after which the concrete grout is poured onto the false floor.

It is, of course, essential that the upper surface of the monolithic concrete floor shall be level and at the proper height. This is attained by first supporting a number of parallel screeds, from the false floor, in such a manner that their upper surfaces lie in the same horizontal plane and which form guides and supports for a straight edge.

25 The supporting and the adjustment of these screeds, as now done, is very laborious and therefore costly.

It is the object of this invention to produce a simple supporting member resembling 30 somewhat a large spike provided with two pointed ends and a head near one end. These members can be driven into the false floor and adjusted with their heads at such a height above the upper surface of the false floor 35 that, when the screeds are driven onto the upper sharpened ends until their lower surfaces come into contact with the upper surface of the heads, the upper surfaces of the screeds will lie in a plane which is at the 40 level for the upper surface of the concrete floor.

The above object and others that may become apparent as the description proceeds are attained by means which will now be described in detail, reference for this purpose being had to the accompanying drawing in which the invention has been illustrated and in which:

Fig. 1 is a transverse section of a concrete 50 floor showing the falsework and the screeds in place;

Fig. 2 is a section taken on line 2—2, Fig. 1;

Fig. 3 is a section to an enlarged scale, taken on line 3—3, Fig. 1. 55

Fig. 4 is a side elevation of my improved screed supporting member;

Fig. 5 is a section taken on line 5—5, Fig. 4; Fig. 6 is a section taken on line 6—6, Fig. 4; and 60

Fig. 7 is a view, partly in elevation and partly in section, showing an anvil applied to the sharpened upper end during the driving of the support.

In the drawing numeral 1 designates the 65 false floor which may be of plank or boards, and which is supported on cross beams 2 that in turn are supported on posts 3. If columns are desired, proper boxes 4 are provided. Reinforcing bars 5 are put in place and held the 70 proper distance above the upper surface of the false floor by some suitable supporting means 6. For the purpose of determining the thickness of the concrete and for leveling the upper surface thereof, screeds 7 must be supported at spaced intervals and in substantially parallel relation. The upper surfaces of screeds 7 must be so adjusted that they lie in the plane of the upper surface of the concrete floor slab 8. For the purpose of supporting these screeds I have provided a novel spike or pin 9 which forms the subject of this invention and which comprises a cylindrical iron rod having one end pointed as indicated by numeral 10. Near the other pointed end 11 is 75 an enlargement 12 which corresponds to the head of an ordinary spike. The end 11 which extends upwardly from the head 12 is preferably of a smaller cross sectional area than the part 9 and tapers to a point. When the 80 screeds are to be put into place, a number of supports 9 are driven into the false floor and aligned. In driving these supports into place it is necessary to protect the pointed end 11 and this is accomplished by applying to the 85 end 11 an anvil 13 which has an axial opening 14 of sufficient length and diameter to receive the end 11 and permit it to rest upon the upper surface of the head 12. The supports are 90 driven into the false floor until the upper surface of the heads 12 are at such a distance from the upper surface of the false floor that the upper surface of the screeds will be at the proper height to correspond with the thickness of the concrete, which has been design- 95

ated by letter *d* (Figs. 1 and 2). If letter *t* 100

designates the thickness of the screeds, then the upper surface of the heads 12 must be placed a distance of $d-t$ from the upper surface of the false floor.

5 If the false floor is carefully laid so as to be level, the support 9 may be driven into the floor until the shoulders 12 are at the proper distance from the upper surface thereof, but if the false floor is not carefully laid, the 10 shoulders 12 must be aligned by a straight edge or other means so as to assure that the upper surfaces of the screeds will be straight and lie in a horizontal plane. After the supporting members 9 have been put into place, 15 the screeds are laid on the sharp points of the tips 11 and driven onto these tips until they rest on the upper surface of the heads 12. If the screeds are made of soft wood, no difficulty will be experienced in driving them onto the 20 ends 11, but if the wood is very hard it may be necessary to bore small holes at the proper points so as to obviate the danger of driving the supports farther into the false floor.

25 After the screeds have been properly placed and adjusted, the concrete grout is poured onto the falsework and tamped down. The level of the upper surface is determined by drawing a straight edge 15 (shown dotted in Fig. 2) along the screeds. After the concrete 30 has set the screeds may be removed and the grooves filled with concrete.

If a wooden floor is to be put on top of the

concrete, the screeds may be made of dovetail shaped strips, properly spaced and are left so as to serve as nailing strips. 35

Where it is contemplated to use a carpet covering, nailing strips may be supported near the walls along all four sides of the room.

From the above description it will be apparent that I have produced a simple support 40 that can be cheaply made and which can be conveniently put into place and adjusted for the purpose of supporting the gauge screeds and which will therefore reduce the cost of laying concrete floors of this type. 45

Having described the invention what is claimed as new is:

50 A member adapted to serve as a support for a screed and as a means for holding the screed in adjusted position with respect to a falsework, said member consisting of a metal rod of uniform cross section having one end sharpened so as to adapt it to be driven into the underside of a screed, and having a shoulder 55 where the sharpened portion joins with the body of the member, the other end of the rod being sharpened so as to adapt it to be driven into a supporting falsework to any extent required to maintain the screed straight regardless of the inequalities of the supporting surface. 60

In testimony whereof I affix my signature.

JOHN S. O'HARE.
